UNITED STATES PATENT OFFICE.

WILLIAM S. A. WILDER, OF VALLEJO, CALIFORNIA, ASSIGNOR TO WILDER MANUFACTURING COMPANY, OF VALLEJO, CALIFORNIA. A CORPORATION OF CALIFORNIA.

DEVICE FOR REMOVING AND REPLACING RAILROAD TIES.

1,403,277.

Specification of Letters Patent. Patented Jan. 10, 1922.

Application filed May 24, 1920. Serial No. 333,640.

To all whom it may concern:

Be it known that I, WILLIAM S. A. WILDER, a citizen of the United States, residing at Vallejo, in the county of Solano and State of California, have invented a new and useful Improvement in Devices for Removing and Replacing Railroad Ties, of which the following is a specification.

This invention relates to a device for removing and replacing railroad ties and especially to improvements on the structure shown in my Patent No. 1,078,182, issued November 11, 1913, and entitled "Device for removing and replacing railroad ties."

One of the objects of the present invention is to provide a simple, substantial, easily operated device by which the old ties supporting a railroad track may be easily removed and replaced by new ties without disturbing or removing the soil of the surrounding road bed.

Another object of the invention is to provide novel means for securing the device in position on the rails when in operation and in conjunction therewith means permitting adjusting of the device when rails of varying size are encountered or when working on curves.

Another object of the invention is to provide means to prevent short circuiting between rails when working so as to avoid accidental operation of block signals, alarm systems or other electric actuated devices when employed.

Another object of the invention is to provide a novel pawl and lever bearing support by which power is transmitted when removing and replacing ties, and also to provide an adjustable plow as will be hereinafter described.

Further objects will hereinafter appear.

The invention consists of the parts and the construction, combination and arrangement of parts as hereinafter more fully described and claimed, having reference to the accompanying drawings, in which—

Fig. 1 is a side elevation of the railroad tie removing and replacing device showing it in operating position on the rails.

Fig. 2 is an enlarged detail side elevation of the same partly in section.

Fig. 3 is a cross section on line 3—3, Fig. 2.

Fig. 4 is a cross section on line 4—4, Fig. 2.

Fig. 5 is a cross section on line 5—5, Fig. 2.

Fig. 6 is a central vertical longitudinal section of the plow.

Fig. 7 is a perspective view of one of the track gripping members.

Fig. 8 is a perspective view of an adjustable track gripping member.

Fig. 9 is a perspective view of one of the safety pawls employed.

Fig. 10 is a perspective view of the screw block.

Fig. 11 is a perspective view of a locking pawl which either limits the movement of the main operating lever, or permits excess movement thereof to release the pawls.

Fig. 12 is a perspective view of the adjustable plow.

Fig. 13 is a perspective view of the bearing member whereby the rack pawls and the operating lever are supported.

Referring to the drawings in detail, A indicates in particular a road bed upon which is placed the usual form of ties 2 and rails 3.

The purpose of the present invention, as previously stated, is to provide means by which old or partially rotted ties may be removed and replaced by new ones without disturbing or removing the surrounding soil or gravel in the road bed. This is accomplished by providing a special form of tie jack, which consists of a pair of parallel disposed interspaced side plates 4, suitably secured together or as here shown by means of bolts 5. Carried by the plates 4, upon rollers 7 appropriately journalled between the plates 4, is a longitudinal pusher bar 8, to which is secured a pair of rack bars 9 and 10. These rack bars are engaged by pawls 11 and 12, of which there are two pair, one pair engaging with the rack bar 9, and the opposite pair with the rack bar 10. The pawls are carried by and are disposed in opposite sides of a bearing member 13, which also serves as a support for a main operating lever 14, in which is secured a pair of opposed handles 15.

The detail construction of the bearing member 13 is shown in Figs. 5 and 13. The bearing member consists of a pair of rings 16, secured or formed integral with plates 17. These plates are interspaced, as at 18, and are provided with superposed recesses 19 for the reception of the respective pawls 11 and 12, one set of pawls being supported in the recesses 19 and the opposite set in the recesses 19a. The bearing members or rings

16 therefore serve as a support for the pawls, and also for the main operating lever as the upper ends of the plates 17 terminate in a bracket 20, to which the handles of the 5 main operating lever 15 are secured by introduction into socket members 21. The upper ends of the pawls are provided with head members 22, which are adapted to be received by the recesses 19 and 19^a. These recesses 10 permit pivotal movement of the pawls therein, and also secure the pawls against endwise removal, lateral removal of the pawls being avoided by exterior securing plates 23. (See Figs. 2 and 5.) The ring-shaped bearing members 16 are supported in journal members 16^a, formed integral with the side plates or secured thereto by means of rivets 24, (see Fig. 1,) and anti-friction rollers 25 are interposed between 15 the journal members 16^a and the ring-shaped bearing sections 16 to reduce friction to a minimum. The opposite pairs of pawls 11 and 12, as previously stated, are pivotally mounted in the recesses 19 and 19^a supporting 20 the same, and their outer ends are thus free to drop by gravity into engagement with the rack members 9 and 10. A rocking or oscillating movement transmitted to the bearing members 16 by means of the 25 handles 15 will therefore impart a reciprocal movement to the pawls 11 and 12, thereby causing these to engage the teeth of the rack bars alternately and transmit movement thereto in the direction of arrow *a*. 30

35 One end of the bar 8 is provided with a downwardly projecting jaw 26, which is adapted to engage with the end of a tie (see Fig. 1,) and as the bar travels in the direction of arrow *a*, when a rocking movement 40 is transmitted through the handles 15, it can be seen that the jaw will engage the tie and force it inwardly in under the rails, thus removing the old tie and simultaneously inserting a new tie. To limit the rocking movement of the rack member or lever 14, I provide a latch 27. This latch is shown 45 in Figs. 1, 2 and 11, and merely consists of a plate which is pivotally mounted between the side plates 4. The upper two pins 28 50 formed on the plate 27 engage the upper edge of the plates 4 and thereby prevents it from dropping downwardly between the same. The lower pins pass through the plates 4 and serve as a pivotal mounting for 55 the same. Downward rocking movement of the lever 14 is limited when the bracket 20 strikes the plate 27. This prevents the pawls from being lifted out of engagement with the rack teeth when ordinarily operating, 60 but reversal of the plate 27 by swinging it backwardly permits a further rocking movement of the lever 14 which is sufficient to lift the pawls 11 and 12 out of engagement with the rack teeth. This excess movement 65 is however only resorted to when it is desired

to pull the push bar 8 to extended position when a new tie is to be inserted.

For the purpose of limiting the outward movement of the push bar 8, I form a notch 28^a at one end thereof. This notch is engaged by a pawl 29 when the notch registers therewith, this pawl being provided for no other purpose than that of limiting the outward movement of the push bar. A handle 30 is formed thereon which permits 70 lifting the pawl if it should be desirable to entirely remove the push bar, for instance for inspection, repairs or otherwise.

In order to secure the tie jack upon the rails when it is placed in position with relation to a tie, it is accomplished by forming suitable recesses 32 in the lower edges of the side plates 4, which are adapted to straddle the tracks as shown in Fig. 1. Secured to the side plates 4, and connecting the same, 80 is a gripping member 33 which is more clearly illustrated in Figs. 1, 2 and 7. The gripping member consists of a longitudinally extending center portion 34, having a width equal to the spacing between the 85 plates 4. This portion is drilled, as at 35, and bolts passing therethrough secure the gripping member between the plates. The gripping member is otherwise provided with a pair of cross arms 36, a pair of rearwardly 90 extending brace arms 37, and a pair of engaging shoes 38. These shoes pass under the base flange of the rail as shown in Fig. 1, and thereby secures the jack as a whole 95 against lateral movement with relation to the rails. The gripping member just described is not only secured to the side plates by means of bolts passing through the drilled openings 35, but it is also secured thereto by tie rods 39 and fastened at its 100 upper end as at 41, and at their lower ends engages perforated ears 40 formed adjacent or integral with the shoes 38. The tie rods 39 are of considerable importance as they materially brace the engaging shoes 38 and thereby relieves the cross and brace arms 36 105 and 37 of excess strain when the jack is in 110 operation.

A gripping or engaging member, similar to that shown in Fig. 7, is employed for the 115 purpose of engaging the opposite rail. This member is shown in Figs. 2, 3 and 8, and is identical to the engaging member shown in Fig. 7, with the exception that longitudinal adjustment is provided to take care of rails 120 of varying size and to increase the distance between the engaging members when working on curves. The longitudinal center section of the engaging member shown in Fig. 8 is provided with a rectangular-shaped 125 opening extending therethrough. This opening is lined with an insulating member 44, side insulating plates 45 and 46, and with an end boss 47, which is plugged by an insulating member 48. Extending through the 130

insulating member 44 is an elongated metallic bushing 49, and extending therethrough is a pair of bolts 50 (see Fig. 2) which supports the engaging member shown in Fig. 8 between the side plates. In other words the elongated bushing 49 is rigidly secured between the side plates 4, while the engaging member proper is slidably mounted thereon. This engaging member is provided with 10 shoes 38^a, perforated lugs 40^a and tie rods are attached thereto, as at 50^a. The upper ends of these tie rods are connected with straps 51, but the tie rods are insulated therefrom by inserting insulating bushings 15 52. Rigidly secured between the side plates 4, rearwardly of the engaging members shown in Fig. 8, is a block 53, in which is formed a threaded central opening 54. An adjusting screw 55 passes therethrough and 20 engages the insulating plug 48 carried by the engaging member. Turning movement of the screw in one direction will cause the engaging member to travel forwardly, thereby decreasing the distance between the respective pairs of engaging members, while 25 turning movement of the screw 55 in the opposite direction will permit rearward movement of the engaging member or increase of distance between the same; this being important as it permits adjustment when rails 30 of varying size are encountered and when working on curves.

In operation when it is desired to remove the tie 2 indicated in Fig. 1, it is accomplished by placing the tie jack upon the tracks in such a position as to cause the depressions 32 to straddle the rails 3, thereby permitting the shoes 38 and 38^a of the respective engaging members to engage the base 40 flanges of the rails and secure the jack as a whole against endwise movement or lateral movement with relation to the rails, exact adjustment of the shoes 38 being obtained by turning the screw 55 until the desired adjustment is obtained. The locking plate 27 is now swung about its pivot to assume a position opposite to that shown in Figs. 1 and 2. This permits the operating lever 14 to be rocked to such an extent that the respective pawls 11 and 12 will be raised out of engagement with the rack bars 9 and 10. The outer jaw 26 may then be grasped and the push bar as a whole pulled outwardly until further movement is stopped by the pawl 29 engaging the notch 28. A new tie, such as indicated at 2^a, is now placed between the old tie and the jaw 26 and a rocking movement is transmitted to the lever 14 by means 55 of the handles 15, the plate 27 being swung back to normal position to limit said rocking movement as previously described. The rocking movement is continued and will of course cause the respective pairs of pawls 11 and 12 to alternately engage the rack teeth

and thereby transmit a longitudinal movement to the pusher bar in the direction of arrow *a*. A sufficient endwise pressure is in this manner exerted upon the tie 2^a, which engages the old tie 2 to force this endwise out from 70 under the rails and similarly to push the new tie into position.

In some instances it often happens that the old tie becomes so decayed or deteriorated that the space occupied by the same is 75 considerably less than that occupied by a new tie. It thus becomes necessary to remove a film of earth, of sufficient thickness to make place for the new tie. This is accomplished by interposing a plow member 80 such as indicated at 60. (See Figs. 1, 6 and 12.) This plow member consists of an end plate 61, a pair of side plates 62, and an inclined centrally disposed scraping plate or plow 63. Formed in the plow plate 63, near 85 its upper end, is a slot 64, and extending therethrough is an arm 65, on the outer end of which is formed a flanged pusher plate or a head 66. This head is adapted to be raised and lowered, together with the arm 65, and a rear head member 67 formed thereon. The rear head member, together with the pusher plate 66, are provided with pins 68 at opposite ends, which extend through inclined slots 69 formed in the respective 90 side plates 62. An adjusting screw 70 is interposed between the rear head member 67 and the end plate 61 and thereby transmits a forward or rearward movement to the arms 65 and the head members 66 and 67 100 carried thereby. This permits raising, lowering and lengthening of the plow, or in other words, adjustment to take care of ties of varying size. The plow when interposed between the new tie to be inserted and the old tie to be removed, as shown in Fig. 1, 105 shaves the required film of earth or gravel as it travels under the rails, the material removed working upwardly on the inclined plow plate 63 and discharging at each side 110 thereof. The plow is not only handy when removing the old decayed ties, but also when inserting new ties which may be slightly larger than the old ties employed. It is therefore useful and in many instances almost indispensable.

When operating or working on a track it can readily be seen that the tie jack as a whole straddles the tracks and would, under ordinary conditions, form a short circuit 120 between the same. This has proven very objectional where block signals, alarm systems, and other electric actuated devices are employed. I therefore insulated one of the engaging members, or that shown in Fig. 8, 125 both with relation to the side plates and also with relation to the tie rods attached thereto, by employing insulating bushings 52. (See Fig. 3.) Short circuiting or accidental operation of electric actuated signals is thus 130

avoided and interference of any kind with railway operation can be prevented as the jack may be quickly removed or replaced to permit the passage of trains, etc.

5 The bolts 5, securing the side plates together, serve as bearings for the rollers 7, between which the pusher bar travels, and these in turn serve as spacers between the plates and thereby eliminating further unnecessary mechanisms or complications.

10 The jack here shown is exceedingly simple and substantial in construction. There is only one adjustment provided, to-wit, the rear engaging member and the adjusting screw 55 employed in conjunction therewith. Unskilled labor may be employed due to the simplicity and compactness of the structure, and it may therefore be operated by any one without skilled attention or supervision.

15 20 While certain features of the present invention are more or less specifically illustrated, I wish it understood that various changes in form and proportion may be resorted to within the scope of the appended 25 claims, similarly that the materials and finish of the several parts employed may be such as the experience and judgment of the manufacturer may dictate or varying uses may demand.

30 Having thus described my invention, what I claim and desire to secure by Letters Patent is—

35 1. In a device of the character described a frame adapted to straddle and engage the rails of a track, a pusher bar longitudinally slidable in the frame, means for transmitting movement thereto, and insulating means carried by the frame to prevent an electric short circuit through the frame between the 40 rails.

45 2. The combination with the rails and ties of a railway, of a gripping or engaging member, one end of which has the longitudinal center formed with a rectangular opening extending therethrough, a lining of insulating material fitting said opening, a metallic bushing extending through the insulating lining and bolts securing the bushing.

50 3. In a device of the character described the combination with the rail straddling frame, of a member secured to one end of the frame adapted to engage one of the rails, a second member adjustably secured to the 55 frame engageable with the opposite rail, and means for insulating the adjustable member with relation to the frame and the rails to prevent an electric short circuit between the rails.

55 60 4. In a device of the character described a frame adapted to straddle the rails of a track, a member secured at one end thereof, a pair of shoes on said member engageable with the base flange of one of the rails, a 65 second member carried by the frame, a pair

of shoes formed thereon engageable with the base flange of the opposite rail, and means permitting adjustment of said member and the shoes carried thereby with relation to the frame and the rail.

5 In a device of the character described 70 an engaging member having a rectangular opening formed therein and extending therethrough, a lining of insulating material fitting said opening, side insulating plates 75 having tubular end bars with a plug of insulating material, a metallic bushing extending through the first named insulating lining, bolts extending through the bushing to support the engaging member, shoes 80 with perforated lugs and tie rods connected with a tie jack, and having an intervening bushing of insulated material.

6 In a device of the character described 85 a frame comprising a pair of interspaced plates adapted to straddle the rails of a track a pair of recesses formed in the plates for the reception of the rails, a rail engaging member secured between the frame plates engageable with the base flange of one of the 90 rails, a second member engageable with the base flange of the opposite rail, said member being adjustably secured to the frame, a pusher bar longitudinally slidable between the main frame plates, a downwardly projecting head member on said bar adapted to engage the end of a rail supporting tie, and manually actuated means supported by the frame plates for imparting a longitudinal movement to the pusher bar and means for 95 insulating one of the rail engaging members with relation to the rails and the frame.

7 In a device of the character described 100 a frame comprising a pair of interspaced plates adapted to straddle the rails of a track, a pair of recesses formed in the plates for the reception of the rails, a rail engaging member secured between the frame plates engageable with the base flange of one of the 105 rails, a second member engageable with the base flange of the opposite rail, said member being adjustably secured to the frame, a pusher bar longitudinally slidable between the main frame plates, a downwardly projecting head member on said bar adapted to 110 engage the end of a rail supporting tie, manually actuated means supported by the frame plates for imparting a longitudinal movement to the pusher bar, and means for insulating the frame with relation to the 115 rails to prevent an electric short circuit between the rails.

8 In a device of the character described 120 the combination with the main frame plates of a member secured between the same, insulation interposed between said member and the frame plates, a rail engaging member slidably mounted thereon between the frame plates, interspaced shoes on said member engageable with the base flange of the 125 130

rail and an adjusting screw engageable with the rail engaging member to impart a longitudinal movement thereto.

9. In a device of the character described 5 the combination with the main frame plates of a member secured between the same, insulation interposed between said member and the frame plates, a rail engaging member slidably mounted thereon between the 10 frame plates, interspaced shoes on said member engageable with the base flange of the rail, an adjusting screw engageable with the rail engaging member to impart a longitudinal movement thereto, perforated lugs formed 15 adjacent each shoe, tie rods connected to the frame plates at their upper ends and the perforated lugs at their lower ends, and means forming an insulation between said tie rods and the frame plates.

20 10. In a device of the character described the combination with the frame plates and the pusher bar slidably mounted between the same, of a bearing member journaled between the plates, said bearing member 25 comprising a pair of ring-shaped members, a bracket connecting the same, a pair of recesses formed in opposite sides of said bracket, two pairs of pawls pivotally mounted in said recesses, means securing the respective pairs of pawls against lateral movement, and means for imparting an oscillating movement to the bracket, the bearing member secured thereto and the pawls carried by the bracket member.

35 11. In a device of the character described the combination with the frame plates and the pusher bar slidably mounted between the same, of a bearing member journaled between the plates, said bearing member 40 comprising a pair of ring-shaped members, a bracket connecting the same, a pair of recesses formed in opposite sides of said bracket, two pairs of pawls pivotally mounted in said recesses, means securing the respective pairs of pawls against lateral movement, means for imparting an oscillating movement to the bracket, the bearing member secured thereto and the pawls carried by the bracket member, and means for limiting the oscillating movement of the bracket member.

50 12. In a device of the character described the combination with the frame plates and the pusher bar slidably mounted between the same, of a bearing member journaled between the plates, said bearing member comprising a pair of ring-shaped members, a bracket connecting the same, a pair of recesses formed in opposite sides of said bracket, two pairs of pawls pivotally mounted in said recesses, means securing the respective pairs of pawls against lateral movement, means for imparting an oscillating movement to the bracket, the bearing member secured thereto and the pawls car-

ried by the bracket member, and means for limiting the oscillating movement of the bracket member, said means comprising a pivotally mounted plate adapted to be swung into or out of engagement with the bracket member so as to either limit the oscillating movement of the same or to permit excess movement of the same.

13. In a device of the character described 75 a pair of interspaced frame plates, a pusher bar slidably mounted between the same, a pair of rack bars, one on each side thereof and secured to the pusher bar, a pair of ring-shaped bearing members journaled between the frame plates, a fork-shaped 80 bracket member connecting the same, two pair of superposed recesses formed in the lower end of the bracket member and two pair of pawls pivotally mounted therein, one pair engageable with one rack member and 85 the other pair engageable with the other rack member.

14. In a device of the character described 90 a pair of interspaced frame plates, a pusher bar slidably mounted between the same, a pair of rack bars, one on each side thereof and secured to the pusher bar, a pair of ring-shaped bearing members journaled between the frame plates, a fork-shaped 95 bracket member connecting the same, two pair of superposed recesses formed in the lower end of the bracket member, two pair of pawls pivotally mounted therein, one pair engageable with one rack member and the other pair engageable with the other rack 100 member, anti-friction rollers interposed between the ring-shaped bearing members and the frame plates, means for transmitting an oscillating movement to the bracket member, and means for limiting said oscillating movement.

15. In a device of the character described the combination with the main frame and the pusher bar supported thereby, of a downwardly projecting head member on 110 one end of the push bar adapted to engage a rail supporting tie, a plow member adapted to be interposed between a pair of aligned ties when one of the ties is engaged by the head member, and means permitting vertical 115 adjustment of the plow member to engage ties of varying size.

16. In a device of the character described 120 a plow member, and means permitting adjustment thereof to engage ties of varying sizes.

17. The combination with the railroad tie removing and replacing device of the character described, of a pusher bar, a frame in which said bar is slidably mounted, means 125 for securing the frame to the track, a downwardly extending head member formed on the outer end of the pusher bar adapted to hold and engage one end of a new tie, a plow member adapted to be secured between the 130

other end of the tie and the old tie to remove any material which might obstruct the path of the new tie, means for transmitting movement to the pusher bar to remove the old tie and replace a new tie, and means permitting adjustment of the plow member to engage ties of varying size.

18. In a railway tie removing and replacing device, a frame comprising a pair of interspaced plates adapted to straddle the track rails, recesses formed in the plates to engage the rails, a rail engaging member secured between the frame plates engageable with the base flange of one of the rails and 10 having an insulating material between it and the frame, and a second member engageable with the base flange of the opposite rail, said member being adjustably secured to the frame.
- 15 19. A railway tie removing and replacing device, including a pusher bar, a frame in

which said bar is slidably mounted, means for securing the frame to the track, insulating means to prevent the transmission of electric currents, a downwardly extending 25 head member formed on the outer end of the pusher bar acting to engage and hold one end of a new tie, a plow member secured between the opposite end of said tie and the old tie to remove surplus material, means 30 for transmitting movement to the pusher bar to remove the old tie and replace a new tie, and means permitting adjustment of the plow member to permit engagement with ties of varying size. 35

In testimony whereof I have hereunto set my hand in the presence of two subscribing witnesses.

WILLIAM S. A. WILDER.
